LLOYD V. LEWIS, OF EDGEWOOD BOROUGH, PENNSYLVANIA, ASSIGNOR TO THE UNION SWITCH & SIGNAL COMPANY, OF SWISSVALE, PA., A CORPORATION OF PENNSYLVANIA.

RAILWAY-TRAFFIC-CONTROLLING APPARATUS.

1,425,397.

Specification of Letters Patent. Patented Aug. 8, 1922.

Original application filed November 25, 1918, Serial No. 263,969. Divided and this application filed March 24, 1921. Serial No. 455,139.

To all whom it may concern:

Be it known that I, LLOYD V. LEWIS, a citizen of the United States, residing at Edgewood Borough, in the county of Allegheny and State of Pennsylvania, have invented certain new and useful Improvement in Railway-Traffic-Controlling Apparatus, of which the following is a specification.

My invention relates to railway traffic con-

10 trolling apparatus, and has for an object the provision of simple and reliable means for transmitting to a railway vehicle indications of traffic conditions in advance without mechanical or electrical contact between devices 15 on the vehicle and devices in the trackway.

The present application is a division of my co-pending application filed November 25, 1918, Serial No. 263,969, for railway traffic controlling apparatus.

20 I will describe one form of apparatus embodying my invention, and will then point out the novel features thereof in claims.

The accompanying drawing is a diagrammatic view showing one form of railway traffic controlling apparatus embodying my invention.

Referring to the drawing, the reference characters H and H' designate the track rails of a railway, which rails are divided 30 into block sections A—B, B—C, etc., by insulated joints 2. Each section is provided with a track circuit comprising the two track rails of the section, a track battery 3, and a track relay designated by the reference character F with an exponent corresponding to the location of the relay. These 35 track relays are employed to control the indications transmitted to the vehicles travelling along the railway, in a manner herein- 40 after explained.

Located in block section A—B is a vehicle V (a railway car or train) which is represented by two axles and two pairs of wheels. This vehicle is provided with apparatus 45 which I will now describe.

Mounted on the vehicle is an electron tube K comprising a vacuum bulb 4, containing a filament 5, a plate 6, and a grid 7 between the filament and the plate. The filament 5 is 50 constantly heated to incandescence by a battery 8 through a circuit which is obvious

from the drawing. Between the grid 7 and filament 5 an alternating difference of potential is maintained due to sustained oscillations in a circuit a which is tuned to resonance at a predetermined frequency, and the oscillations in this circuit a are in turn maintained by a portion of the energy output from the plate circuit of the electron tube K. Circuit a comprises a condenser 11 and the secondary 12 of a transformer T³. The terminals of the condenser are connected with the filament and grid respectively of the electron tube K, a blocking condenser 9 being included in the connection as shown. A high resistance or "grid leak" 10 is optionally connected in multiple with the condenser 9 in order to prevent the accumulation of an excessive negative charge on the grid 7. The plate circuit for electron tube K is from a battery 13 through wires 14 and 55, primary of transformer T, wire 18, primary 19 of transformer T³, wire 20 to plate 6, thence through the tube K to battery 13. The electron tube K is thus connected in such manner that it acts as a self-excited generator of pulsating current, of a frequency which is determined by the constants of circuit a. This frequency I will term the "given" frequency. 80

The plate circuit just traced is coupled to a second oscillating circuit b by a transformer T, so that oscillations are sustained in circuit b by energy from the plate circuit. Circuit b passes from the secondary of transformer T, through wire 56, contact 57 of a relay R, wire 58, condenser 22, primary of a transformer T¹, wire 59, coil 23, and wire 60 to the secondary of transformer T. Coil 23 is wound on a laminated soft iron core 24 which is U-shaped as shown, with its legs projecting downwardly, and the plane of the core is parallel to the track rails H and H'. Located at certain points in the trackway are bars D of soft iron, preferably laminated, each of which bars is also parallel with the track rails, and is so positioned that it is directly under and close to the open ends of core 24 as the vehicle passes over the bar. The elements in circuit b are so proportioned that when core 24 is not influenced by a bar D, this circuit is resonant. 95 100

at the given frequency, so that oscillations of considerable amplitude then exist in circuit *b*. When core 24 passes over a trackway bar D, however, the reluctance of the magnetic circuit of this core is considerably reduced, so that the inductance of coil 23 is greatly increased. Circuit *b* is then not resonant at the given frequency, hence the amplitude of the oscillations in this circuit is greatly reduced.

The reference character K' designates a second electron tube, the plate circuit for which is from battery 13, through wires 14 and 67, winding 66 of relay R, winding 64 of this relay and condenser 65 in multiple, wire 63, thence through electron tube K', and wire 62 to battery 13. Relay R controls a brake application magnet M, the circuit being from battery 27, through the winding 20 of magnet M and contact 50 of relay R, to battery 27. The magnet M controls brake application apparatus of any suitable form, in such manner that an automatic application of the brakes occurs whenever this magnet becomes de-energized.

The secondary circuit of transformer T' constitutes the grid circuit for tube K', and this circuit, which is designated *c*, is from the secondary of transformer T', through wire 61, condenser 46, wires 62 and 60, coil 44, and wire 68 to the secondary of transformer T'. The terminals of the condenser 46 are connected with the filament and grid respectively, of the electron tube K', a blocking condenser 47 being inserted in this connection as shown. Coil 44 is wound on a laminated soft iron core 45 which is U-shaped, with its legs projecting downwardly, and is arranged transversely with respect to the track, as shown in the drawing. Located in the trackway adjacent each bar D is a conductor W, which is at times supplied with alternating current by means herein-after explained. When the vehicle-carried core 45 passes over a conductor W in which alternating current is flowing, part of the magnetic lines of force surrounding the conductor pass through the core 45 and so induce an alternating potential in the coil 44, whereupon sustained oscillations are produced in the resonant circuit *c*, provided the alternating current in the conductor W is of the given frequency. This produces an alternating difference of potential between the grid and filament of the electron tube K', whereby an alternating component is produced in the current in the plate circuit of K' which contains the windings of relay R. Since this relay is of the well known induction motor type, it is not affected by the continuous or steady component of the current in this circuit, but by reason of condenser 65 connected across the terminals of winding 64, the alternating components of the currents through windings 64 and 66 are dis-

placed in phase to produce a rotating field to cause the rotor to close its contacts 50 and 57.

As stated hereinbefore, the electron tube K is so connected that it serves as a generator of pulsating current, the frequency of which depends on the frequency to which circuit *a* is tuned (the "given" frequency). The current in the plate circuit of electron tube K produces alternating current of the same frequency in the coupled oscillating circuit *b*, which circuit is normally tuned to resonance at the frequency of such current. Circuit *b* is coupled loosely with circuit *c* through the medium of transformer T', and circuit *c* is likewise tuned to resonance at the same frequency as circuit *a*. The current thus induced in circuit *c* produces an alternating difference of potential between the grid and filament of electron tube K', and thus produces a pulsating current component of the same frequency in the plate circuit of electron tube K', this pulsating component being of sufficient amplitude to effectively energize relay R. When, however, core 24 passes over one of the trackway bars D, the resonance of circuit *b* at the given frequency is destroyed so that the current which then flows in this circuit is comparatively weak. The current which is then induced in circuit *c* is likewise weakened, so that the current in the plate circuit of electron tube K' is then insufficient to effectively energize relay R. The de-energization of relay R is prevented, however, if the adjacent conductor W is supplied with alternating current of the frequency to which circuit *c* is tuned. In this event, the sustained oscillations are maintained in circuit *c*, so that the plate circuit for electron tube K' carries pulsating current of sufficient amplitude to energize relay R or to keep this relay energized if it is already in such condition.

It follows from the foregoing that the frequency of the current supplied to the trackway conductors W must be the same as that to which circuits *a*, *b* and *c* are tuned.

Each block section is provided with one of the bars D, which bar is located at maximum braking distance in the rear of the entrance end of the section. Adjacent to each of the bars D is one of the conductors W, this conductor preferably extending a short distance beyond each end of the adjacent bar D. Each conductor is supplied at times with alternating current of the given frequency, this supply being controlled by the track relay for the corresponding section. For example, the ends of the conductor W in the rear of point B are connected with the terminals of the secondary of a transformer E, and the circuit for the primary of this transformer is from the secondary of transformer J^B, through contact 52 of track 130.

relay F^B , wire 53, primary of transformer E, and wire 54 to the secondary of transformer J^B . Conductor W in the rear of location C is similarly supplied with current 5 from a transformer J^C , this supply being controlled by track relay F^C . The primary of each transformer J is connected with a transmission line L, which line is constantly supplied with alternating current 10 from a suitable source, such as a generator G.

The operation of the apparatus is as follows: As long as core 24 is not over one of the trackway bars D, relay R will be effectively energized, so that magnet M will be energized. When the core 24 passes over one of the bars D, if the adjacent conductor W is supplied with current, relay R will continue to be energized, but if such conductor W is not supplied with current, relay R will open and so will de-energize magnet M to cause an automatic brake application. When core 24 passes away from bar D, relay R will remain de-energized because circuit b 25 includes a contact 57 of this relay which is closed only when the relay is energized.

The section immediately in advance of location C being occupied by a vehicle V', track relay F^C is de-energized; but inasmuch as 30 block section B-C is unoccupied, relay F^B is energized so that the conductor W controlled by this relay is supplied with alternating current. Vehicle V is assumed to have just entered block section A-B. Relay R on this vehicle is, of course, energized, and brake magnet M is consequently energized, so that the vehicle is free to proceed into block section A-B. When the vehicle reaches such a position that the core 24 35 passes over the trackway bar D, the inductance of circuit b will be increased to such extent that relay R would open. Just before this occurs, however, core 45 will pass into the magnetic field surrounding the conductor W, so that relay R will be held closed by the 40 current induced in coil 44; magnet M will, therefore, continue to be energized and no automatic application of the brakes will occur. Vehicle V can, consequently, proceed 45 into block section B-C without interference on the part of the automatic apparatus.

Inasmuch as track relay F^C is de-energized, the conductor W in the rear of location C is not supplied with current. It follows that when vehicle V reaches such 50 point that its core 24 passes over the bar D in block section B-C, relay R will open, and that upon leaving the bar this relay will remain open, because circuit b is open at 55 contact 57. The opening of relay R will de-energize magnet M so that an automatic application of the brakes will immediately occur, and the vehicle will be brought to a stop before it reaches location C.

60 65 In order to allow the vehicle to proceed

after an automatic brake application has occurred, a push button 76 is provided which is normally open but which, when closed, closes a shunt around contact 57 of relay R and so closes circuit b even though relay R is de-energized. This push button is preferably located at such a place on the vehicle that it is accessible only from the ground, thus requiring the vehicle to come to rest before the button can be operated. Assuming, 70 then, that the vehicle has been brought to rest by an automatic application of the brakes, the operator descends to the ground and pushes button 76, thus energizing relay R. The closing of relay R will energize 75 magnet M so that the brakes will again be released and the vehicle may proceed.

Although I have herein shown and described only one form of apparatus embodying my invention, it is understood that 80 various changes and modifications may be made therein within the scope of the appended claims without departing from the spirit and scope of my invention.

Having thus described my invention, what 90 I claim is:

1. Railway traffic controlling apparatus comprising a vehicle, a circuit on said vehicle supplied with alternating current and containing inductance and capacity, a relay 95 supplied with current from said circuit and effectively energized when the circuit is closed and the inductance therein has a given value, said relay operating when de-energized to open said circuit, devices located in 100 the trackway for changing the value of the inductance in said circuit sufficiently to effectively de-energize said relay, trackway means for energizing said relay independently of said circuit and governing means on 105 the vehicle controlled by said relay.

2. Railway traffic controlling apparatus comprising a vehicle, a circuit thereon supplied with alternating current, and containing inductance and capacity, a relay supplied with current from said circuit and effectively energized when the inductance in such circuit has a given value, devices located in the trackway for changing the value 110 of the inductance in said circuit to a sufficient extent to effectively de-energize said relay, trackway means for energizing said relay independently of said circuit, and governing means on said vehicle controlled by said relay.

3. Railway traffic controlling apparatus comprising a vehicle, a circuit on said vehicle supplied with alternating current and containing inductance and capacity, an amplifier controlled by current in said circuit, 115 vehicle governing means supplied with current by said amplifier and normally held in inactive condition, devices located in the trackway for temporarily changing the inductance of said circuit to an extent suffi- 120 125 130

1. cient to render said governing means active, and other trackway devices for supplying alternating current to said amplifier to nullify the effect of the first devices on said governing means.
2. Railway traffic controlling apparatus comprising a vehicle, a circuit thereon supplied with alternating current and containing inductance and capacity, a relay supplied with current from said circuit and effectively energized when the circuit is closed and the inductance therein has a given value, devices located in the trackway for temporarily changing the value of the inductance in said circuit to a degree sufficient to effectively de-energize said relay, means controlled by said relay when de-energized for opening said circuit, trackway means for energizing said relay independently of said circuit, and governing means on the vehicle controlled by said relay.
3. Railway traffic controlling apparatus comprising a vehicle, a resonant circuit thereon including a source of alternating current, a relay supplied with current from said circuit and effectively energized when the circuit is resonant, said relay operating when de-energized to open said circuit, devices located in the trackway for temporarily destroying the resonance of said circuit and thereby de-energizing said relay, trackway means for energizing said relay independently of said circuit, and governing means on the vehicle controlled by said relay.
4. Railway traffic controlling apparatus comprising a vehicle, a resonant circuit thereon including a source of alternating current, an amplifier controlled by current in said circuit, vehicle governing means supplied with current by said amplifier and held in inactive condition when said circuit is resonant, trackway means for temporarily destroying the resonance of said circuit and thereby rendering said governing means effective, and other trackway devices for supplying alternating current to said amplifier to nullify the effect of the first-mentioned devices on said governing means.
5. Railway traffic controlling apparatus comprising a vehicle, a circuit thereon supplied with alternating current and containing inductance and capacity, a second circuit on the vehicle receiving energy inductively from the first circuit, vehicle governing means controlled by the second circuit and normally held in inactive condition, devices located in the trackway for temporarily changing the value of the inductance in said first circuit to a sufficient degree to render said governing means active, and other trackway means for supplying current to said second circuit to maintain said governing means in inactive condition independently of the condition of the first circuit.
6. Railway traffic controlling apparatus comprising a vehicle, a circuit thereon including a source of alternating current, said circuit being normally tuned to resonance at the frequency of said source, a second circuit on the vehicle receiving energy inductively from the first circuit and tuned to resonance at said frequency, a relay controlled by said second circuit and arranged to be effectively energized when the first circuit is resonant, said relay operating when de-energized to open said first circuit, devices located at intervals in the trackway for temporarily destroying the resonance of said first circuit and thereby de-energizing said relay, other devices located in the trackway for supplying current of said frequency to said second circuit, and vehicle governing means controlled by said relay and held in inactive condition when the relay is energized.

In testimony whereof I affix my signature.

LLOYD V. LEWIS.
